ROD OR TOOL CONNECTER

Joseph H. Blake, Seattle, Wash.

Application February 12, 1934, Serial No. 710,955

2 Claims. (Cl. 287—103)

My present invention relates to the art of coupling devices and more particularly to a rod or tool connector.

There are many conditions of use where it is desirable to couple together shafts, pipes or tool bits in a manner which will permit taking the full compression load, by abutting the two elements joined together, in such a manner that the shock of hammering and compression strain will not fall upon the coupling mechanism. This is true of control rods and the like and most particularly in the case of percussion tools. It is for this latter purpose that my invention has been conceived and developed altho it is believed it will be clearly understood that there will be many other uses which will suggest themselves to those skilled in this art.

In percussion tools it is very desirable to have drill bits which are easily interchangeable yet which will absorb the full blow of the percussion tool. This can only be accomplished by having an extension of the plunger element of the percussion tool engage in end to end contact the tool bit itself. My device is particularly intended to serve this purpose and by virtue of the fact there is no screw connections, no threads to become battered and in fact no load placed upon the coupling device itself, it can be depended upon to last for long periods under the most unusual conditions.

Other and more specific objects will be apparent from the following description taken in connection with the accompanying drawing, wherein

Figure 1 is an elevation showing my device as used in holding a tool bit to the plunger of a percussion tool. Figure 2 is a longitudinal sectional view taken thru the device of Figure 1, the cutting plane being revolved 90 degrees from Figure 1. Figure 3 is a view similar to Figure 1 showing certain parts of my device in section to better illustrate the construction. Figure 4 is a view similar to Figure 3 excepting the coupling device is shown in its released position where the tool is free for removal. Figure 5 is a cross sectional view taken along the line 5—5 of Figure 4. Figure 6 is a cross sectional view taken along the line 6—6 of Figure 3.

Referring to the drawing, throughout which like reference characters indicate like parts, 8 designates the base sleeve of my coupler. This should be fixedly secured in some convenient manner to the tool plunger or striker element 10. For sake of clarity in my present drawing I have shown this sleeve being secured to piston 10 by the thru rivet 12. In actual practice, probably,

it would be most desirable to thread it onto plunger 10 or possibly weld or braise it to the same. Sleeve 8 as will best be seen from Figures 3 and 4 is provided with a slot throughout its lower extent as 14. The lower end of this slot is of limited width, just sufficient to pass a lug 16 which should be fixedly secured to member 18 which might be a tool bit or one element of a control rod. Slot 14 has a portion of increased width at 20 which is adapted to house the wedge lug 22. Slot 14 is further enlarged at its upper end and on the opposite side from enlargement 20 as at 24 in an amount sufficient to nearly house lug 16. This enlargement should not however be the full thickness of lug 16 otherwise the wedging action of wedge block 22 will be lost. It should further be provided with a flat side 26 of sufficient length so that lug 16 will have a bearing surface, parallel to its axis of movement, of a greater extent than its possible movement.

Encircling base sleeve 8 is the wedge lug sleeve 28. This sleeve fits sufficiently loose on sleeve 8 so that it may slide thereon being restrained in its movements only by the inwardly extending lug 22 which in the present illustrations I have shown as being riveted to sleeve 28. In actual construction any suitable means of securing this lug might be employed. Lug 22 is wedge shaped after the showing of Figures 3 and 4 and is of such a width that it can be passed thru slot 14. It is further provided with the cam surface 30 which is adapted to engage lug 16. In the drawing I have indicated lug 16 as a pin. This is suitable for most installations, however, where extreme strength and long resistance to wear is required it might be desirable to make lug 16 of considerable extent along shaft 18 so that a bearing surface would be provided which would engage cam surface 30 instead of the line of contact which now exists. Wedge lug 22 is normally held in its engaged position by the urgency of spring 32 which in turn is backed up by collar 34 secured as by threading thereto by means of set screw 36 to base sleeve 8. In constructing a coupler of this type it must be borne in mind that collar 34 must be so positioned and spring 32 so proportioned that the movement of sleeve 28 will be sufficient to place wedge block 22 in the locked position shown in Figure 3 and in the relieved position shown in Figure 4.

Method of operation

In operating my device, sleeve 28 is forced downwardly against spring 32 until the position indicated in Figure 4 is reached. It is then pos-

sible to insert the shaft or tool bit 18 and to carry it upwardly until shaft 18 is in intimate contact with shaft 10 as is illustrated in Figures 2 and 3. Shaft 18 may then be revolved slightly with respect to shaft 10 after the showing of Figure 3 and the slide collar 28 released or the wedge may be relied upon to revolve it. Wedge block 22 then assumes the position shown in Figure 3 and it is impossible to retract tool 18 without again slipping collar 28 downwardly. In this position it will be noted that lug 16 engages the flat surface 30 so that a limited movement is provided. This makes extreme accuracy of placement of lug 16 immaterial and accommodates the tool to a certain degree of wear and when in such a position lug 16 is not required to absorb any of the percussion load. The same is true of a compression load such as might be experienced in a control rod assembly.

20 The foregoing description and the accompanying drawing are believed to clearly disclose a preferred embodiment of my invention but it will be understood that this disclosure is merely illustrative and that such changes in the invention may be made as are fairly within the scope and spirit of the following claims.

I claim:

1. In a coupling for a percussion tool, the

combination with a reciprocable striker and a socket-sleeve fixed at one end to the striker, said sleeve having a slot opening at its other end and a lateral locking-recess in the closed end of the slot, of a slidable tool in the sleeve, an exterior lug on the tool seated in said recess and adapted to pass through the open end of the slot, a cam-sleeve slidable and partially rotatable on the socket-sleeve, an inner cam lug rigid with the cam sleeve and engaging the exterior lug, and 10 said slotted sleeve having a release-recess to receive the cam lug to permit detachment of the tool.

2. In a tool coupling the combination with a socket-sleeve having an open-end longitudinal slot, said slot having a locking-recess in one wall at its inner end and a release-recess in its opposite wall at the rear of the locking-recess, of a detachable tool having a locking lug to enter the locking recess, a cam-sleeve slidable on the 20 socket-sleeve, an interior lug on the cam-sleeve adapted to seat in the release-recess, a cam edge on the interior lug for locking the first lug in the locking-recess, an end collar on the socket-sleeve, and a spring coiled about the socket-sleeve and interposed between the cam-sleeve and the end collar.

JOSEPH H. BLAKE.
